UNITED STATES PATENT OFFICE.

HARRY E. FORSLUND, OF MINNEAPOLIS, MINNESOTA.

ENGINE-VALVE-SETTING GAUGE.

Application filed January 5, 1925. Serial No. 551.

To all whom it may concern:

Be it known that I, HARRY E. FORSLUND, citizen of the United States, residing at Minneapolis, in the county of Hennepin and 5 State of Minnesota, have invented certain new and useful Improvements in Engine-Valve-Setting Gauges; and I do hereby declare the following to be a full, clear, and exact description of the invention, such as 10 will enable others skilled in the art to which it appertains to make and use the same.

This invention relates to a device for properly adjusting the opening and closing position of the inlet and exhaust valves on 15 an internal combustion engine, such as an automobile engine.

Such engines usually comprise a plurality of cylinders and it is necessary that the inlet and exhaust valves open and close at 20 the definite time in relation to the engine cycle or the movement of the piston in each cylinder. Heretofore the setting of the valves has generally been done by turning over the engine and having a mark on the 25 fly wheel which would be alined with the mark on a stationary part of the engine. It is a great deal more convenient, especially if only one person is working on the engine, to set the valve opening and closing according to the position of the piston and the 30 piston is, of course, moved in definite relation to the revolution of the crank shaft or fly wheel.

It is an object of this invention, therefore, 35 to provide a very simple and efficient device, by means of which the setting of the valve can be properly made in relation to the position of the piston in the cylinder.

It is also an object of the invention to 40 provide a device for determining the setting position of the intake and exhaust valves of an internal combustion engine, which device is adapted to be placed in a cylinder of said engine having a portion constructed 45 and arranged to engage the top of a piston and a portion constructed and arranged to engage the top of the cylinder; said device also having an intermediate or side portion so arranged that the device can also be used 50 to determine a position of the valve when the top of the piston is above the top of the cylinder.

It is more specifically an object of the invention to provide such a device comprising 55 a member adapted to be placed in the engine cylinder having a plane surface or straight

edge adapted to engage the top of the piston and having indications thereon adapted to be alined with the top of the cylinder when the piston is in proper position for the 60 valves to open or close.

These and other objects and advantages of the invention will be fully set forth in the following description made in connection with the accompanying drawings, in 65 which

Fig. 1 is a vertical section through a cylinder showing the piston therein and part of the connecting rod and also showing a view in side elevation of the device in use; 70

Fig. 2 is an edge view of the device; and Fig. 3 is a view in side elevation of the modified form of the invention.

Referring to the drawings, the cylinder 3 of an internal combustion engine is shown, 75 in which is movable the piston 4, shown as having the usual piston rings 5 therein and as connected to the connecting rod 6. In accordance with the present invention, the member 7 is shown adapted to be inserted in 80 the top of the cylinder 3. While the device may be made in various shapes, in the embodiment of the invention illustrated, the same is shown as made from a comparatively wide flat plate having a straight edge 85 or plane end 7^a at one end, which end is adapted to engage the top of a piston. Member 7 has also straight side edges at its angles to edge 7^a adapted to fit against the inner side of the cylinder 3. The plate 7 90 has marks or indications 7^b and 7^c thereon extending normal to its side edges.

In the form of the invention shown in Fig. 3 a flat plate 8 is used which may be of the same thickness as the plate 7 and the plate 8 has a bottom portion or straight edge 8^a adapted to engage the top of the piston when the plate 8 is disposed in the top of the cylinder. The plate 8 has side portions 8^b and 8^c disposed at right angles to the bottom portion 8^a, the side portions 8^b and 8^c being offset respectively to form the shoulder portions 8^d and 8^e, which shoulder portions are parallel to the portion 8^a. The length of the shoulder portions 8^d and 8^e is also determined for a certain type of engine as will be later described. 100 105

In operation of the device as shown in Figs. 1 and 2, when the valves are to be set, member 7 will be inserted into the top of the cylinder with the edge 7^a in contact with the top of the piston. The engine will then be 110

moved until the piston is in position to bring the gauge mark 7^b into alignment with the top of the cylinder or top of the cylinder block, which is usually a flat surface. The 5 mark 7^b will be so placed that when the piston is in this position the intake valve should just be in closed position and the valve can be so set. The engine will then be moved to bring the piston into position with 10 the mark 7^c in alignment with the top of the cylinder or cylinder block. When the piston is in this position, the exhaust valve should begin to open and this valve can be so set. When the valves are thus adjusted, they will 15 be in proper relation to the piston and the movements of the piston and valves will be properly synchronized.

In the use of the device as shown in Fig. 3, the member 8 will be inserted in the top 20 of a cylinder of the engine with the portion 8^a in contact with the top of the piston. The engine will then be turned or moved until the shoulder 8^d comes into flat contact with the top of a cylinder or cylinder block. 25 When the piston is in this position the intake valve will be in closing position and the valve can be so set. If desired, of course, the shoulder 8^d may be first placed in contact with the top of a cylinder or cylinder block 30 with the edge 8^b against the side of the cylinder, and the engine then turned until the top of the piston engages the portion 8^a, at which time the intake valve can be set for closing position. To set the exhaust valve 35 for opening position the portion 8^a will be placed in engagement with the top of the piston within the cylinder and the engine moved until the shoulder 8^e also engages the top of the cylinder or cylinder block. As 40 before stated, the shoulder 8^e might first be placed in engagement with the top of a cylinder or cylinder block and the engine moved until the top of the piston engages the portion 8^a, it being understood that the 45 side 8^b should be in contact with the wall of the cylinder. It is often desirable to also check the setting in the valves as to the opening of the intake valve and the closing of the exhaust valve. In most engines the top of 50 the piston at this time is slightly above the top of the cylinder. The member 8 is so arranged that if the portion 8^e on the side having the shoulder 8^d is placed flat against the top of the cylinder or cylinder block, the 55 portion 8^b on the same side will then just be in engagement with the top of the piston

when the piston is in the proper position for the opening of the intake valve. The piston can thus be so positioned and the intake valve set for its opening position. When 60 the side 8^c on the same side as the shoulder 8^e is placed in flat contact with the top of the cylinder or cylinder block, the portion 8^b on the same side of the device will be in position to be engaged by the top of the piston 65 when the exhaust valve is in proper closing position. The piston can thus be moved and the correct closing position of the exhaust valve determined. By the use of member 8, therefore, the four positions of the valves 70 can be determined directly from the piston and the valves can be set in a very convenient manner.

From the above description, it is seen that applicant has provided a very simple and 75 efficient device which will have high utility in determining the correct opening and closing positions of the intake and exhaust valves in relation to the position of the piston. The device is quite simple and can 80 be easily and inexpensively produced. The same has been used in actual practice and found to be very successful and efficient.

What is claimed is:

A device for determining the setting of 85 the intake and exhaust valves of an internal combustion engine, comprising a member 90 adapted to be placed in a cylinder of said engine and having a straight bottom portion adapted to engage the top of the piston, said member having straight comparatively long 95 side portions extending at right angles to said bottom portion and respectively having at each side shoulder portions extending at right angles to said side portions, said shoulder portions being disposed at different 100 distances from said bottom portion, said shoulders being adapted to engage the top of the cylinder block when the said bottom portion is in engagement with the top of the 105 piston for respectively determining the closing position of the intake valve and the opening position of the exhaust valve, and the portions of said side portions at each side of said shoulders being respectively adapted to engage the top of the cylinder and the top of the piston when the intake and exhaust valves are respectively in opening and closing positions.

In testimony whereof I affix my signature.

HARRY E. FORSLUND.
